(57) **CLAIM**

The ornamental design for a temperature clamp (PT) as shown and described.

DESCRIPTION

The patent or application file contains at least one drawing executed in color. Copies of this patent or patent application publication with color drawing(s) will be provided by the Office upon request and payment of the necessary fee.

1. Temperature clamp (PT)

1.1 : Reference

1.2 : Front

1.3 : Back

1.4 : Left

1.5 : Right

1.6 : Top

1.7 : Bottom 1. The name of this design product: temperature clamp (PT); 2. Use of this design product: The product of this design is a kind of clamp that can hold the pipe to measure the temperature; 3. Design points of this design product: lies in the shape; 4. The picture or photograph that best illustrates the point of the design: Reference.
